UNITED STATES PATENT OFFICE.

GUY DE LA RIGAUDIERE, OF BETHLEHEM, PENNSYLVANIA, ASSIGNOR TO THE TRAV-
ELER RUBBER COMPANY OF BETHLEHEM, U. S. A., OF BETHLEHEM, PENNSYL-
VANIA, A CORPORATION OF DELAWARE.

DESIGN FOR A TIRE.

Application filed February 23, 1922. Serial No. 830. Term of patent 14 years.

To all whom it may concern:

Be it known that I, GUY DE LA RIGAUDIERE, a citizen of the United States, residing in Bethlehem, Northampton County, Pennsylvania, have invented a new, original, and ornamental Design for a Tire, of which the following is a specification, reference being had to the accompanying drawing, forming part thereof, in which:—

Fig. 1 is a plan view of a portion of an automobile tire illustrating my design; and
Fig. 2 is a transverse sectional view on the line 2—2 of the tire shown in Fig. 1.

I claim:

The ornamental design for a tire, substantially as shown.

GUY DE LA RIGAUDIERE.
